UNITED STATES PATENT OFFICE.

CHARLES ALBERT MAYRHOFER, OF VIENNA, AUSTRIA-HUNGARY, ASSIGNOR
OF ONE-HALF TO CARL DIENER, OF SAME PLACE.

ELECTRIC PNEUMATIC-CLOCK SYSTEM.

SPECIFICATION forming part of Letters Patent No. 310,530, dated January 6, 1885.

Application filed March 19, 1884. (No model.) Patented in France December 31, 1883, No. 159,424; in Belgium December 31, 1883, No. 63,721; in Italy December 31, 1883, XVII, 16,273, and XXXII, 347; in Germany January 1, 1884, No. 28,387; in England January 1, 1884, No. 1,681; in Spain June 9, 1884, No. 5,662, and in Austria-Hungary October 10, 1884, No. 770 and No. 46,783.

To all whom it may concern:

Be it known that I, CHARLES ALBERT MAYRHOFER, a subject of Austria-Hungary, residing at Vienna, in the Province of Nether Austria, 5 in the Empire of Austria-Hungary, have invented certain new and useful Improvements in Electrical Pneumatic Clocks; and I do hereby declare the following to be a full, clear, and exact description of the invention, such as will 10 enable others skilled in the art to which it appertains to make and use the same, reference being had to the accompanying drawings, and to letters or figures of reference marked thereon, which form a part of this specification.

15 The object of this invention is to provide means by which any number of clocks connected together by hydropneumatic means may be wound and correctly set every time an electric circuit is closed by a central or 20 standard clock. For this purpose each time the electric circuit is closed by the central or standard clock a liquid under pressure is made to compress a quantity of air and wind up and set all the secondary clocks in the entire 25 system. I accomplish this by first making an electric circuit open or close valves in pipes containing liquid under pressure, and, secondly, the liquid in its turn compresses air and operates the mechanism to produce the 30 result required. The clocks in this system may be of any desired construction—that is, any of the well-known self-acting clocks in common use.

I will now proceed to describe my invention, referring to the drawings forming part of this application, in which the same letters of reference indicate the same parts in the drawings.

Figure 1 is a diagram illustrating a standard or central clock and secondary clock with the electric hydropneumatic means for controlling said secondary clocks, which will be hereinafter fully explained. Fig. 2 is a perspective view of an electric magnet with appliances for opening valves and setting the liquid in motion. Fig. 3 is a like view of the valves and cock regulator for governing the

flow of the liquid. Fig. 4 shows the two air-compressing chambers with their connections. Fig. 5 is a perspective view of my safety devices by which the liquid is prevented from entering into the air-pipes in case of accident or other disturbances. Fig. 6 is a perspective view of mechanism for restoring the electric magnet and the valve-regulator to their normal position. Fig. 7 shows a box containing a counting or indicating mechanism and means for operating it. Fig. 8 represents the rear of a clock having both the appliances for sending a current of electricity to the line and the means for winding and setting the secondary or line clocks.

From each central station any number of secondary clocks may be controlled and wound up. The standard clock at the central station 65 may itself be controlled by any other standard clock (as from an astronomical observatory) by electric hydrostatic and pneumatic means; or it may be even itself controlled by one of the line-clocks.

70 For the sake of convenience I have shown in the diagram in Figs. 1 and 8 a clock which has both the circuit-closers of the central clock and means for sending an electric impulse out on the line and devices for winding and setting the secondary or line clocks.

75 Commencing with the central clock, I will now describe my system.

Q is the central-clock mechanism or standard time-piece, the center or minute arbor of 80 which has a contact-wheel, R, and a spur-wheel, q, rigidly fastened to it and meshing with a pinion, q', attached to another contact wheel or disk, R', which is calculated to make eight rotations to one of wheel R. These 85 wheels are made of metal or conductive material, and are provided with bosses or projections r r'. When these wheels are set in motion by the clock mechanism, the said bosses or projections make contacts simultaneously at 90 certain intervals with the central spring, S and S', and close the electric circuit through the train of wheels, wire w', plate 3 of switch-board V, cross-plate S, connected to plate 3

by a switch-pin, thence by wire W^2 , thence to electro-magnet B through circuit I^3 and I^4 in the safety devices, (to be hereinafter fully described,) thence back through the switch-board V, by plates 9 and 4, and wire w^5 , local battery X, and wire w , to contact S of the standard or central clock.

It is obvious that, instead of having a local circuit such as above described, a main-line circuit can be used.

In the diagram Fig. 1, I show a main-line wire, x , leading to point W', thence through the lightning-arrester W, wire x' , plates 6 and 8 of the switch-board, wire w^2 , through the circuit-breaker I^3 and I^4 and electro-magnet B, thence back through wire w^4 , plates 9 and 5, wire x^2 , thence through the lightning-arrester to main line x^3 . When the electric circuit is closed through contact-points S S' of the central or standard clock, the electro-magnet B (see Fig. 2) is energized and attracts its armature b, fastened to shaft b^2 by arm b' , causing the shaft to turn slightly and carry the arm b^5 , also attached to said shaft b^2 , backward. This arm b^5 has a lug or support, b^6 , upon which normally rests the end of lever C, and when the lug b^6 is turned backward the end of lever C is allowed to drop down. The lever C is pivoted upon an upright, c , and at its fulcrum end is provided with a reinforcement, c' , upon which rests a pin, c^2 , adjustably fastened to the end of lever-arm c^3 , which latter is free to turn on the bearing d^3 . When the lever C drops down, the arm c^3 falls off the pin c^2 by the help of a weight (not shown) hanging on rod c . The said arm c^3 is fastened to the beam D by means of the slotted segment d and set-screw d^2 . The weight on rod c causes the beam D to oscillate and carry with it the weight d^2 to the position shown in dotted lines, Fig. 2. The slotted segment d and set-screw d^2 allow the angle between arm c^3 and weight d^2 to be regulated at pleasure. The said beam D bears segments at both ends, and is provided with projecting pins $e' e' e' e'$, by means of which the arms e^2 and e^3 , fastened to the plugs of the valve-cocks D' and D², are moved into the position shown, or into the position indicated by dotted lines, in order to open one of the valve-cocks and close the other. The upper parts of these valve-cocks are connected together by a curved pipe, D³, and the lower part of valve-cock D' communicates by means of a pipe, y, with the main conduit Y of a city or other water-supply, and cock D² connects by means of pipe y' with exit-main Y' of said city water-supply. The curved pipe D³ is also connected with another branch pipe, D⁴, which leads to the valve-cock regulator, Fig. 3. When the lever C falls down—that is to say, every time the electric circuit is closed by the central clock—the valve-cock D' is opened, valve D² is closed. In consequence of this the water or other liquid flows from the conduit Y or main supply through pipe y and valve-cock D' into the

curved pipe D³, thence through branch pipe D⁴ into valve-cock E³, Fig. 3, which in its normal position is open. This valve-cock is connected by means of pipe f with a cylinder, F, whose piston bears a rack, F'. The liquid entering the said cylinder raises the piston and rack and partially rotates the pinion I², which has two sets of gears, and which meshes with the teeth of sector f', fastened to the plug of valve-cock E³, and turns down said sector, and at the same time turns upward the sector f², fastened on valve-cock E². In this manner valve-cock E³ is opened and valve-cock E² is closed. The pinion F² is provided with a flange or disk, and guides the rack F'. A small roller, g², bearing on the rear of the segment, also acts as a guide for the said rack. By the lowering of the toothed sector f', which is provided with pins or tappets f³ f³, the arm f¹, fastened on the plug of the valve-cock E³, is forced downward and the valve-cock E² is closed. When the sector is raised, the said cock is opened.

As illustrated in Fig. 3, valve-cock E³ stands closed and valve-cocks E² and E³ stand open. If, now, the liquid enters cylinder F, it raises the rack F', which opens valve-cock E² and closes E³, and then the liquid flows from the conduit Y or main supply into the pipe y', and from thence by branched pipe and stop-cocks h² h' into the air-chambers G G, as shown in Fig. 4. This compresses the air therein contained and forces it through h² h' and valve-cocks h³ h² into pipe z. The two air-chambers are not ordinarily needed, but are both used when one is not sufficient to perform the labor of winding and setting all the secondary cocks h⁴ h¹ and supply-valves. h⁵ is a manometer, and h⁶ h⁶ are gage glasses. Before this compressed air is allowed to act upon the secondary cocks it passes through what I term a "safety apparatus." (Best shown in Fig. 5.)

As before stated, pipe z conducts the compressed air from the air-compressors and conveys it into the cylinder K' of the said safety apparatus, from which it passes through the air-pipe z², that communicates with the secondary cocks. The cylinder K' contains a float, K², that does not prevent nor hinder the passage of the air; but it is raised whenever liquid or water enters cylinder K'. The float K² has an upright rod that passes through a small stuffing-box, and is provided at its top with a button, K³. If the float K² is raised, button K³ raises one end of lever K, fastened to the shaft k, and partially turns it. The arm k', also fastened to shaft k, has a lug, which holds wheel i from rotation by pin i², resting on said lug. The partial turning of the shaft k releases the pin i² from end of the path of the lug, and the wheel i is rotated by the weight i² and cord i' in the direction of the arrow. The arbor of wheel i carries a pinion, I², which gears with the sector I', fastened to the plug of valve-cock I². By the turning of the wheel i and pinion I² the sector is raised

and the valve-cock is closed and stops the flow of liquid from the main supply.

In order to indicate disturbances or accidents at the central-clock station, an electric circuit breaker is placed in the path of the sector. This consists of two metallic spring-arms, I^3 and I^4 , which are normally in contact. The spring-arm I^4 is longer than the spring-arm I^3 , and as the sector I is moved up it strikes the arm I^4 and separates the contact-points, breaking the circuit, which has been before described. This interruption may be made visible at the central station in any well-known manner.

15 Any disturbances in working caused by lack of water may be indicated at the central-clock station. A small pipe, l , leads from the conduit Y to the cylinder L , the piston of which is maintained in an elevated position as long as the pressure of liquid or water is not interrupted. If leaks occur in conduit Y , the weight L on the piston-rod will press down upon the opposite end of the lever K and operate the safety apparatus in the same manner before described.

20 In Fig. 3 is also shown a trough, M , having in its center a hollowed or receiver recess, M' , which contains a float, M^2 . The purpose of this device is to cut off the water-supply in case of the breakage of a pipe, gage-glass, &c. This float M^2 bears an upright rod, m , provided at its lower end with a collar, m' . If the water rises in the receiver M , the float is raised and collar m' lifts the slotted end of lever m^2 and closes the valve-cock M^2 of the main conduit Y , and at the same time the upper end of rod m raises lever K and closes valve-cock I and breaks the electric circuit, as before set forth.

25 It is seen from the foregoing that if the central cock is arranged to make and break an electric circuit at regular intervals of time a current of water or liquid will flow at the same intervals and compress the air in the cylinder, and force it to wind and set the secondary or line clocks. To produce this effect several valve-cocks are opened and closed and several levers and weights are brought into operation. In order to restore all these parts to their normal position after they have been so operated the line air-pipe z^2 is connected to what I term a "reverser" (see Fig. 6) by means of a branch pipe, z' . This branch pipe leads to the air-cylinder N . As long as the pressure of air in the line-pipes is not sufficient to raise the piston N' , with its weight N^2 , the piston will remain on the bottom of the cylinder; but as soon as the pressure is great enough to raise said piston and its weight the arm n' , connected to said weight, as shown, will lift one end of the lever n^2 , fastened to the plug of valve-cock O' , by means of which the valve-cock is opened and the compressed air flows through it to another branch pipe,

30 z^2 , leading to air-cylinder E , Fig. 2, raising a piston or weight contained therein with rod

c , which latter being loosely attached to the lever-arm c^2 , it is also raised and turns the beam D and restores it and lever C to their normal position, ready for action when the central clock again closes the circuit. The spring attached to a lug on shaft b^2 draws back arm b^3 , and the support b^6 again rests thereon. It is obvious that valve-cock D' is closed by this restoring movement. The valve-cock D^2 now being open, the water contained in cylinder F of the valve-cock regulator, Fig. 3, will be discharged through f , E^2 , and D^2 , and valve-cock D^2 to exit-pipe Y' by means of a weight hung at g on the sector f^2 , which forces down the rack F' and its piston.

35 In order to indicate the number of times that the circuit has been closed by the central or standard clock, a registering or counting mechanism is connected to the branch air-pipe z' . The compressed air, entering the cylinder P , lifts a piston which operates said register. This register may be of any well-known construction. The air compressed as has been described passes through the air-pipes $z z^2$ and any other branch pipes to the secondary or line clocks, for the purpose of winding and setting them.

40 For the sake of convenience I have shown the mechanism for performing these functions attached to the central clock, as I have before stated; but in practice these devices are attached to the secondary or line clocks. Every time the circuit is closed by the central clock compressed air is forced into the cylinder U of each line or secondary clock and raises rod t^2 , and with it the end of the winding-lever T , connected to said rod. Said lever is fulcrumed at its other end on the winding-arbor s of the clock. A pawl, t' , is attached to the lever T , and as the lever is raised the pawl, taking into the teeth of the ratchet-wheel t , winds the clock in the direction of the arrow; but before this is done the setting mechanism is operated, which I will first describe. The lever T has at about its center a pin, u , projecting inwardly, that moves the setting-lever T' to one side to set the hands of the clock. This lever has at its upper end fork-shaped projections t^2 . A crank-arm is fastened to the minute-hand arbor, and has a projecting pin, u^2 , and rotates with said arbor. If the clock should gain or lose a few minutes in a day, it is set correctly by the arm T' being forced toward the minute-hand arbor, the arm u^2 being brought to zero, or correct time, by the forked projections moving against said arm, and thereby setting the minute-hand forward or backward, as the case may be, to the correct time, or to agree with the central clock.

45 In order to set these clocks quickly and certainly and avoid stopping, means are employed to operate the lever T rapidly. To effect this the lever is constructed with a bent or inclined portion, as shown in the drawings, Fig. 5. A spring, v , having a projection, v' , is fastened on the side of the lever T' . When

the lever T is raised by the force of the air in the cylinder U, the pin u pushes up on the inclined projection v', forcing the lever T' and its fork t' inward, as above described. When 5 it has passed the upper part of the projection v', it is forced back to its normal position by the spring v', as seen. Until this is accomplished the winding of the clock is not commenced, as a small pin, w', is fastened to 10 the back plate of the clock in such a position that the pawl t' on lever T is kept out of contact with the teeth of the ratchet-wheel t while the lever T is down and until the pin u passes the incline v'. The pawl t' is then 15 released, and, taking into the ratchet-wheel, winds the clock to the upward limit of movement of lever T. A small spring (not shown in the drawings) controls the pawl t'. The 20 clocks are therefore only partially wound every time the electric circuit is closed by the central clock through the hydraulic pneumatic means which I have described. When wheels R and R' are set in motion, the bosses r r' make 25 contacts simultaneously at certain intervals with the springs S and S', and close the electric circuit through the train of gearing, wire w', plate 3 of switch-board v, connected with plate 8 by a switch-pin, thence by wires w' to electro-magnet B, through circuit I' I', 30 thence back through the switch-board V by plates 9 and 4, and wire w', local battery X, and wire w, to contact S of standard central 35 clock. When the electric circuit is thus closed through the points S S', the electro-magnet B (see Fig. 2) is energized and attracts 40 armatures fastened to shaft b' by arm b', causing the shaft to turn slightly and carry the arm b', attached to said shaft, backward. This allows the lever C to drop and permits the 45 arm c' to fall off the pin c'. This causes the beam D to oscillate and carry with it the weight d' to the position shown in dotted lines in Fig. 2. When the lever C falls—that is to say, every time the circuit is 50 closed by the central clock—the valve-cock D' is opened and valve D' is closed, and the water flows from conduit Y through pipe j and valve-cock D' into the curved pipe D', thence through branch pipe D' into valve-cock E', Fig. 3, which in its normal position 55 is open. The liquid then enters cylinder F, raises the piston and rack, and partially rotates the pinion F', and through the intermediate gearing turns down the sector f', opening the cock J' and closing cock E'. This 60 compresses the air contained therein and forces it through h' h' and valve-cocks h' h' into pipe z. The compressed air then passes through the safety device H, and from thence 65 through pipe z' to the secondary clocks. When the pressure becomes great enough to raise the piston N', with its weight N', the arm h', connected to said weight, will lift one end of the lever n', fastened to the plug of valve-cock O, opening said valve-cock and permitting 70 the compressed air to flow through it and

branch pipe z' to air-cylinder E, Fig. 2, raising the piston or weight contained therein with rod e, which lifts the lever-arm c', turns the beam D, and restores it and lever C to 75 their normal position, ready for action when the central clock again closes the circuit.

Having thus described my invention, what I claim, and desire to secure by Letters Patent, is—

1. The combination, with the center or minute arbor of a central clock or standard time-piece, of a contact-wheel and spur-wheel rigidly fastened thereto, a similar contact-wheel having a pinion meshing with the spur-wheel, 80 and the contact-springs S and S', the contact-wheels being provided with bosses adapted to make contact at proper intervals with the contact-springs to close the electric circuit, substantially as specified. 85

2. The combination, with the central clock and its contact-wheels and gearing and the contact-spring and plates, of the switch-board connected to the said plates by means of suitable conductors, a line connecting with an electro-magnet, and the hydropneumatic devices operated by said magnet, substantially as 90 specified.

3. The combination, with the electro-magnet and its armature and the water supply and 95 discharge pipes and their valves, of the mechanism, substantially as described, whereby said valves are alternately opened and closed by the electrical impulses established by the makes and breaks at the central clock, substantially as specified. 100

4. The combination, with the electro-magnet and its armature and the lever to which 105 said armature is attached, (the lever resting against the end of the same,) the pivoted arm operated by said lever, and its weighted rod, of the adjustable beam having segments at its end, the weighted oscillating lever, and the alternately opening and closing valve-cocks operated by projections on the segments of the 110 adjustable beam, substantially as specified.

5. The combination, with the weighted pulley i, its pinion, and the segment I', operating the valve-plug of the valve I, the lever K', engaging a lug, i', on the pulley, the lever K, 115 mounted on the fulcrum-shaft k, the float K', located in a well, k', and having a rod provided with a button, K', at its upper end, setting under the free end of the lever K, to operate the same and release the wheel i, 120 substantially as and for the purpose specified.

6. The combination, with the lever K, the wheel i, and valve-operating segment I', of the float M', located in a well, M', the float-rod m, having a collar, m', and the valve-lever m', 125 for automatically opening and closing the valve M', substantially as specified.

7. The combination, with the lever K, the weight L', and the cylinder L, of the float K' and float-rod K', whereby the lever K is actuated to release the wheel i', substantially as 130 described.

8. The combination, with the segment I' and its actuating mechanism, of the circuit-breaker connected by suitable conductors with the central clock, whereby interruptions or breakages 5 in the hydraulic devices are indicated, substantially as specified.

9. The combination, with the segments $f^2 f^4$, of the pinion F^2 , pulley g^2 , the rack F' and piston, the cylinder F and pipe f , valve E^3 10 and pipe D^4 , and the valves E' and E^2 and connecting-pipe y' , all arranged to operate substantially as specified.

10. The combination, with the clock-regulating devices, of the reservoirs G and the 15 connecting-pipes y', p , and h , and the cylinder K' , connecting with said reservoir by means of a pipe, z , and with the regulating mechanism, substantially as specified.

11. The combination, with the cylinder E , 20 of the pipe z^2 , valve O' , the valve-arm n^2 , bent arm n' , having a slot through which said valve-arm extends, the weight N^2 , having a piston-rod and piston, and the cylinder N' , connecting with the pipe z' , substantially as and for 25 the purposes specified.

12. The combination, with the pipe z' , of the cylinder P and its piston, and the levers, pawl and ratchet, and registering mechanism whereby the number of impulses established by the 30 central clock may be registered, substantially as specified.

13. The combination, with the cylinder U , connected to the pipe z^2 , and the piston-rod t' , of the lever T , having a lug, u , and the bent 35 lever T' , having an inclined bearing, v' , against which the lug works, and the fingers t^2 , adapted to engage the crank-arm u^2 , and the spring v^2 , bearing against said lever to hold and return it to normal position, substantially as and 40 for the purpose specified.

14. The combination, with the lever T and its actuating mechanism, of the ratchet t , se-

cured to the winding-shaft S , and the pawl v^2 , the setting mechanism, and mechanism for holding the said pawl from the ratchet-teeth 45 during the setting of the clock, substantially as specified.

15. The combination, in an electro-hydro-pneumatic-clock system, with a standard or central clock and a series of secondary or controlled clocks, of a reversing apparatus, substantially as described, for returning the valves and levers to their normal position after each actuation of the circuit, substantially as described.

16. The combination, in an electro-pneumatic-clock system, with a standard clock and a series of secondary or controlled clocks, of safety device and gearing operated thereby, substantially as described, for giving a warning signal when an accident has occurred in any of the circuits, substantially as set forth.

17. The combination, with means for winding and setting a series of clocks, substantially as set forth, of devices consisting of a reservoir connected to the air-pipe, and having a weighted piston operating, substantially as described, for returning the valves and levers to their normal position, as set forth.

18. The combination, substantially as hereinbefore set forth, with means, as described, for controlling a series of secondary clocks, or devices for closing the water-supply in case of accident, the same consisting of a trough having a float and float-rod, which actuates a lever to close the water-supply cock, substantially as set forth.

In testimony whereof I affix my signature in presence of two witnesses.

CHARLES ALBERT MAYRHOFER.
